HIRAM WOLF, OF ST. LOUIS, MISSOURI, ASSIGNOR TO HIMSELF
AND ABRAM D. WOLF, OF SAME PLACE.

Letters Patent No. 95,061, dated September 21, 1869.

IMPROVEMENT IN MINING-PUMPS.

The Schedule referred to in these Letters Patent and making part of the same.

To all whom it may concern:

Be it known that I, HIRAM WOLF, of St. Louis, in the county of St. Louis, and State of Missouri, have invented a new and useful Improvement in Pumps; and I do hereby declare the following to be a full and correct description of the same, sufficient to enable others skilled in the art to which my invention appertains, to fully understand and use the same, reference being had to the accompanying drawings, which make part of this specification, and in which—

Figure 1, Sheet I, is a front elevation of my improvement in pumps;

Figure 2, Sheet II, is a central longitudinal vertical section of one section of the same; and

Figures 3 and 4, Sheet II, are detached vertical sections of the suction and force-pumps.

Figure 5, Sheet III, is a front view of a modification of one of the pumps of my improvement.

Like letters of reference indicate like parts in the several figures.

My invention being applicable to that class of pumps generally, which lift water, for any purpose, from great depths, commonly called five-story pumps, is more especially adapted for mining-purposes, when water has to be lifted from a depth of several hundred feet; and

It consists in the arrangement, above each other, of a series of sections, each section containing a reservoir and two pumps, the discharge-orifice of which pumps is on a level with or above the tops of the reservoir, so that the pumps, after receiving the water by suction, or, more properly speaking, by the weight of the atmosphere, has to force or lift it but the distance of its length, as it flows from the discharge-orifice to the reservoir by its own gravity; this distance being but one or two feet, relieves the piston-rod from the immense weight, which, in this class of pumps, has heretofore proven the great obstacle to elevating water from great depths. These sections are complete in themselves, so that any number of them may be placed one above the other, till they reach the required height or depth, and may be attached to each other in a simple and expeditious manner, the whole of the pumps, attached to the several sections, being operated by one motive-power.

Also, in pivoting the pumps of each section in such a manner that they can be easily brought into a horizontal position, from a vertical one, if, from any cause, it becomes necessary to reach the interior of any of them, and thus any repair can be made, without the necessity of detaching the pumps from the frame.

Also, in connecting each pump with two reservoirs, one on the section next below from which it receives the water by atmospheric pressure, and the other in its own section, into which it delivers the water lifted from the reservoir next below.

Also, in the peculiar construction of the pumps, as hereinafter more fully described.

In the drawings, I have shown but three sections, A, B, C, though any required number of them may be employed.

Each section consists of four uprights D, connected by cross-pieces E, the heads of the uprights being provided with sockets F, into which fit the lower ends of the uprights of the next section above. These sections ought to be made of the same size, so that any number of them may be placed one above the other, with the certainty of fitting.

Attached to the cross-piece E, at opposite sides of the frame of the sections, and separately secured to each section, are flat pieces G, the upper end of each being provided with a plate, H, (see fig. 2,) to which the lower end of the piece G, next above, is secured, thus forming a continuous piece, which may be detached in sections at pleasure.

On these pieces G are secured the pumps I, their discharge-orifice being level with, or above the top of the reservoir J of their own sections.

The reservoirs J may be made of any suitable material, and in any suitable form, and may be attached to their respective sections in any convenient manner.

In the drawings, I have shown the reservoirs provided with a cover, through which pass the connecting-pipes K L, the pipes K being attached to the suction-part of the pumps I, and leading to the reservoir next below, and the pipes L being connected to the forcing-part of the pumps, and leading to the reservoir next above.

The pumps consist of the pumps proper I, (see figs. 3 and 4,) in which the piston i moves on the rod j.

The lower end of the pump is packed, as shown at o, which packing is held in place by a screw-nut, k, through which packing and nut passes the piston-rod, thus enabling me to connect the ends of the piston-rods to each other directly and in a vertical line, so that the power is exerted in a direct line on each piston-rod.

In fig. 5, I have shown a modification of the operation of the piston-rod, to obviate the necessity of passing the same through the lower part of the pumps, so as to prevent any leakage.

The rod j is provided at each pump with an arbor, j¹, to which the short piston-rod j² is attached. This arbor encircles the pump, and is of sufficient size to allow the free movement of the piston-rod, without the arbor touching the pump. By this arrangement, we also gain room in the pump below the piston, as the space taken up by the piston-rod, when it passes through the lower end of the pump, is replaced by water, and thus we gain an increase of one or two pounds of water at each stroke, and the friction of the piston-rod in the lower packing is obviated.

The lower end of the pump I connects with the valve-chamber n of the suction-part, by means of the channel g.

The top of the valve-chamber is closed by a screw-bolt, *f*, the lower end of which is hollow, to receive and guide the stem of the valve *e*.

The lower end of the valve-chamber forms a channel, *d*, connecting with the suction-pipe *K*, which is secured to the valve-chamber by a screw-nut, *c*.

The valve-chamber *b* of the force-pump connects with the lower end of the pump *I*, by means of the channel *a*, (fig. 4,) the valve *m* being arranged in the same manner as the valve *e*, and bears such relation to the latter, that when the piston *i* is moved upward the valve *e* opens, while the valve *m* is closed, and the water drawn by atmospheric pressure from the lower reservoir, through pipe *K*, into the pump.

When the piston descends, the valve *e* is closed and valve *m* opened, and the water forced up to the discharge-orifice, from which it flows, by its own gravity, through pipe *L*, into the reservoir of that section.

The pipes *L* are secured to the upper side of the valve-chamber *b* by screw-nut *b'*.

The piston-rods *j* are connected to each other, by means of the right and left-hand screw-nuts *n*.

The pump proper *I* is, at its back, provided with a flange, *O*, which, again, has formed on it a cross-flange, *P*.

The flange *O* is provided with a slot, in which plays loosely, a nut, *R*, into which one end of a screw, *S*, fastens, which latter passes through the piece *G* and flange *P*.

This screw *S* forms the pivot on which the pump can be turned from a vertical to a horizontal position, when it is necessary to repair or clean it. To keep it in a vertical position, four screws, *s*, pass through the piece *G* into flange *P*.

I have shown the pump *I* attached to the outside of the frame of the sections, as I am thereby enabled to more clearly show their operation. In actual use, I propose to place the same on the inside of the frame, thus saving space and also connecting-pipe, and having the pumps and all working-apparatus protected by the frame.

M represents a walking-beam, pivoted on standards *N*, secured to the standards of the uppermost section, to the ends of which are connected the piston-rods of the pumps of section *A*.

Motion is imparted to the walking-beam in any suitable manner, and the piston-rods of the several pumps being connected to each other, all the pumps are operated simultaneously, one side in the opposite direction of the other, so that a continuous flow into the reservoirs and suction from the same is kept up.

Each section is made of a height of twenty-five feet, or less, so as to enable each pump to lift the water easily, without undue pressure of the atmosphere.

To facilitate the movement of the piston-rod, and to relieve the strain of its weight from the point of attachment to the walking-beam, I attach a cord, *p*, to the connections of the piston-rods, as shown at *r*, which cord passes over a roller, *q*, attached to the frame *D E*, and has attached to it a weight, *s'*, of sufficient size to counterbalance the weight of that sec-

tion of the piston-rod *i*. In this manner, the point of attachment of the piston-rod to the walking-beam is relieved from the weight of the piston-rod.

The operation of my device is easily understood.

A sufficient number of sections having been connected to each other to reach the required depth, motion is given to the walking-beam, and through it to the piston-rods. At each stroke, the pistons of one side descend, while the pistons of the other side ascend. The ascending pistons draw the water through pipes *K* from the well or the bottom of the mine and the several reservoirs, while the descending pistons force the same upwardly into the discharge, from which the water flows, by its own gravity, into the reservoir. At the next stroke the two sides reverse their function. The uppermost reservoir is provided with an efflux-pipe, *J'*, through which the water is discharged. In this manner a constant and steady stream of water is discharged.

If, in employing this pump in mines, the shaft in which it is used is sunk deeper, and it becomes necessary to lengthen the pumps, the top-section may be detached, and any suitable number of sections attached to the pumps, the top-section replaced, and the piston-rods, pipes, and reservoirs connected, when the operation of the pump can be continued.

This pump can be constructed very cheaply, and without much trouble, as the frame may be made out of rough timber, the ends being trimmed to fit into the sockets *F*, which, when rough cast, will be of very little expense.

The reservoirs may consist of open wooden tubs, and the pipes may be led into them in any suitable manner.

The pumps can be cast very cheaply, and the expense of my pumps will be very small compared with pumps now in use for similar purposes.

Having thus described my invention,

What I claim as new, and desire to secure by Letters Patent, is—

1. The arrangement, above each other, of any desired number of sections, as herein described, each section containing one reservoir and two pumps, the discharge-orifices of which pumps are level with or above the top-part of the reservoir, substantially as and for the purpose set forth.

2. The pumps *I*, when pivoted in such a manner that they may be brought from a vertical to a horizontal position, substantially as and for the purposes set forth.

3. The combination of the pumps *I*, flanges *O P*, nut *R*, and screws *S s'*, substantially as and for the purposes set forth.

4. The combination of the pumps *I*, reservoirs *J*, and pipes *K* and *L*, substantially as and for the purposes set forth.

HIRAM WOLF.
